UNITED STATES PATENT OFFICE

OTTO MELIN, OF LIVINGSTON, MONTANA, ASSIGNOR OF ONE-HALF TO CLARENCE ALLEN, OF LIVINGSTON, MONTANA

MECHANICAL IRRIGATOR

Application filed April 14, 1931. Serial No. 530,124.

The present invention relates to improvements in mechanical irrigators and has for an object to provide a mechanical irrigator adapted to travel along the irrigation ditches having the functions of a traveling dam.

Another object of the invention is to provide a self-controlled machine for moving along by its own power guided by the ditch for the purpose of damming and disbursing the water from the ditch over the adjacent land to be irrigated.

A further object of the invention resides in providing a machine containing its own power for propelling a flexible dam along in the irrigation ditch or in one of the lateral ditches, and being so arranged that it will be guided by the banks of the ditch and is adapted to be automatically stopped at or near the end of the ditch.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a plan view of my improved mechanical irrigator in operation.

Figure 2 is a side elevation of the machine.

Figure 3 is a side elevation as seen from the opposite side of that shown in Figure 2, with parts broken away.

Figure 4 is a front elevation of the device as shown in Figure 1, and

Figure 5 is a vertical section taken along the line 5—5 of Figure 1.

Referring more particularly to the drawings, 10 and 11 designate longitudinal beams, 12 represents the transverse beam at the front extending across and secured to the longitudinal beams 10 and 11.

At the front of the device is a vertical standard 13, which may be secured to the frame of the machine in any appropriate way and which serves to support the guide disks or wheels 14 which are preferably of a concavo-convex construction with the convex surfaces disposed outward and in position to engage the side walls of the irrigation

ditch 15, as shown to best advantage in Figure 4. These wheels are mounted upon an axle, the end portions of which are indicated at 16. The axle is carried by the standard 13, U-bolts 17 being indicated as for use in securing this axle to the beam. The ends 16 of the axle extend forwardly and downwardly in divergent relation for carrying the disks 14 at an angle, whereby their convex surfaces will engage the side walls of the ditch and tend to hold the machine in a central position.

The front part of the machine is supported by a swivel guide wheel 18 mounted in the lower fork 19 and also in an upper 65 diagonally extending fork 20, both forks being secured to a pivot rod 21 journalled in appropriate brackets 22 carried by the rear side of the standard 13.

This pivot rod 21 also extends through the 70 transverse bolster 12 to further strengthen the same. Journalled between the longitudinal beams 10 and 11 at the rear of the machine and upon an axle 23 is a traction wheel 24 having cleats or lugs 25 for giving traction. This traction wheel 24 is adapted to travel in the bottom of the ditch and acts as the main support of the machine.

The machine is driven by an internal combustion or other engine or motor 26 mounted 80 upon the frame work and having a variable pulley 27 for driving through a belt 28 a similar cooperating pulley 29. This latter pulley is mounted on a shaft 30, which shaft carries a pinion 31 disposed in mesh with a gear wheel 32 upon a jack shaft 33. The jack shaft 33 in turn carries a pinion 34 disposed in mesh with a gear wheel 35 upon a power shaft 36. These various shafts are journalled in appropriate bearings in the frame of the machine, which includes a diagonal beam 37 which has its front portion secured to the transverse bolster 12 and its rear end divergent away from the longitudinal frame beam 11. At the rear portion of the framework, the shaft 23 may be extended over to the diagonal beam 37 and be secured thereto, but a brace might equally well serve this purpose.

The power shaft 36 is provided with a sprocket 38 engaged by a chain 39 which is also trained about a much larger sprocket 40 upon the shaft of the traction wheel 24.

5 The gearing arrangement may be of any ratio, but it preferably steps the power of the motor up to a very considerable degree, so that with a relatively small motor, the machine may be driven positively over very heavy ground and through the ditches, as required.

There is a land balancing wheel 41 mounted at the rear portion of the machine outwardly beyond the diagonal beam 37, this wheel 41 being carried upon the outer end portion 42 of a crank shaft, the main portion 43 of which is journaled cross-wise in the main frame of the machine. The crank portion 44 of the shaft is adapted to move 20 over a perforated plate 45 fastened to the diagonal beam 37; and which plate is adapted to receive an eye-bolt 46 or other fastening, whereby the crank portion 44 of the shaft may be secured in adjusted position. 25 This is for the purpose of raising and lowering the wheel 41 to correctly align the machine horizontally and to get the proper level and ground adjustments.

30 Extending transversely of the machine and beneath the beams 10, 11 and 37 is a dam or curtain which may consist of loose canvas 47 which is hung from the bars 48 and 49 held to the framework of the machine by bolts or other fastenings 50. The canvas 47 may be 35 partially supported and shaped by light spring steel bands 51, which springs having riveted at the bottom portions thereof a band of leather belting or leather strap 52.

40 In operation, the machine moves along in the ditch under its own motive power and being propelled by contact of the pulley wheel or traction wheel 24 in the bottom of the irrigation ditch. Of course, the engine will provide for the driving of the machine at variable speeds, as required. The machine may be driven along through the lateral ditches, which are small ditches extending off the main ditch for the purpose of actually diverting the water on to the land. The water is actually spread out over the ground from the lateral ditches, and in these lateral ditches, the machine is adapted to travel, being propelled as indicated.

55 The land or idler wheel 41 travels on the surface of the field above the lateral ditch and is adjustable, as previously explained, to different heights, so as to accommodate the machine to any depth of ditch within limits. 60 This wheel 41 is for the purpose of levelling and steadyng the machine, which is automatically guided by the disks 14 at the front, thus compelling the machine to follow the curves in the ditch. Upon either of the disks 65 14 coming in contact with the bank of the

lateral ditch, the pressure of the disk upon the bank causes the machine to move on the pivot wheel 18, and thus the machine is kept in the ditch.

70 The impounding and distributing of the irrigation water is successfully and easily accomplished by the dam or curtain 47, which completely takes the contour of the ditch under the pressure of the water which is dammed by the canvas.

75 The machine, when started, travels slowly across the field along the line of the lateral ditch and distributes the water evenly over the field. No attention is needed from the operator than to start the machine in the ditch, and consequently, the operator is released for the performance of other duties. It will thus be seen that the irrigator is of simple construction and simple in operation and is light and easily handled. The stopping of the machine in the far end of the lateral ditch may be accomplished without personal attention by a stake set in the ditch which engages a light-weight stick connected to the switch of the motor 26 and projected out in front of the machine. Upon striking the obstruction, this stick is forced back, thus throwing off the switch.

80 The dam is dragged along behind the irrigator and is held in place by the weight of the water in the ditch. The irrigator operates from the upper to the lower end of the ditch and travels in the same direction in which the water is flowing. As soon as the water strikes the dam, it causes it to be flexible, and the weight of the column of water makes it conform to the contours of the ditch. 85 Canvas becomes quite heavy when it has been thoroughly soaked and as soon as it is saturated, the water will be dammed up and the canvas dam will remain in place and will move only as it is dragged along by the mechanical irrigator.

90 95 100 105 110 115 120 125 130 135 It will be obvious that various changes in the construction, combination and arrangement of parts could be made, which could be used without departing from the spirit of my invention and I do not mean to limit the invention to such details, except as particularly pointed out in the claims.

Having thus described my invention, what I claim and desire to secure by Letters Patent of the United States is:—

1. In a mechanical irrigator, a wheeled frame for movement through the field, and a dam carried by said frame for moving in the ditch.

2. In a mechanical irrigator, a wheeled frame and a flexible dam carried beneath said frame and cross-wise thereof for extending into the ditch and out along the banks thereof.

3. In a mechanical irrigator, a wheeled frame, an engine on the frame for driving the same through the field, means for guiding the frame above the ditch, and a dam car-

- ried by the frame for extending into the ditch.
4. In a mechanical irrigator, a frame, wheels for supporting the frame and adapted to move in the ditch, guide means at the front of the frame also for moving in the ditch, and a dam carried by the frame and extending into the ditch.
5. In a mechanical irrigator, a frame, wheels on the frame moving in a ditch, a balance wheel on the frame for moving on the land, and a dam carried on the frame for moving in the ditch.
6. In a mechanical irrigator, a frame, a traction wheel on the frame for moving in the ditch, a guide swivel wheel at the front of the frame also moving in the ditch, guide means at the front portion of the frame for engaging the sides of the ditch, and a dam carried by the frame.
7. In a mechanical irrigator, a frame, a traction wheel at the rear portion of the frame, means on the frame for driving the traction wheel, a swivel wheel at the front portion of the frame for traveling in the ditch, guide means in front of said swivel wheel, and a dam carried by the frame behind the swivel wheel.
8. In a mechanical irrigator, a frame, wheels mounted on the frame for travelling in the ditch, a dam carried by said frame, and an adjustable land wheel also connected with said frame.
9. In a mechanical irrigator, a frame, wheels mounted on said frame and in the ditch, a diagonal beam forming a portion of said frame, a land wheel, a crank shaft on the frame for carrying said land wheel, and means on the frame for adjusting said crank shaft to vary the elevation of the land wheel.
10. In a mechanical irrigator, a frame, a traction wheel on the frame, a guide wheel on the frame, an engine installed on the frame, a gear reduction arrangement between said engine and traction wheel, guide means carried by said frame, and a dam also carried by said frame.
11. In a mechanical irrigator, a frame, wheels supporting the frame for movement in a ditch, and disks mounted on the front of said frame for guiding the same in the ditch.
12. In a mechanical irrigator, a frame, wheels on the frame for driving in a ditch, a dam carried by said frame and disks having their convex sides presented outwardly to the side walls of the ditch and being mounted diagonally with respect to the line of travel and to the vertical.
13. In a mechanical irrigator, a wheeled frame, and a dam carried by said frame and including a piece of flexible material and resilient means bearing on said material.
14. In a mechanical irrigator, a wheeled frame, and a dam carried by said frame and including a piece of canvas extending trans-
- versely beneath said frame and into the ditch, and flat springs for engaging said canvas, and leather pieces on said canvas.
15. The combination in an irrigation water distributor of a frame having a traction wheel adapted to support it in part and a dam connected to said frame and adapted to be moved along a lateral thereby and having a shape such that water flowing in the lateral acts on the dam to cause a down pressure on said traction wheel.
16. The combination in an irrigation water distributor, the combination of a wheeled frame, a dam fixed to said frame and adapted to minimize the flow of water past itself and guide disks fixed to said frame and adapted to steer the frame to keep the dam in a given lateral as the distributor moves along it.
17. A frame having a dam thereon arranged to be held in a lateral, means for propelling said frame and guides on said frame adapted to steer said frame so as to maintain said dam in a given lateral while being propelled by said means.
18. A self propelled frame having a dam thereon and guides on said frame adapted to project into a lateral and to steer said frame so that said dam will move along a given lateral.
19. A self propelled frame having a dam thereon and concavo-convex guides on said frame so arranged that their convex faces may contact with the sides of a lateral.
20. The combination in an irrigation water distributor, the combination of a wheeled frame, a dam fixed to said frame and adapted to minimize the flow of water past itself and guide disks fixed to said frame and adapted to steer the frame to keep the dam in a given lateral as the distributor moves along it, said guide disks being adapted to run in the lateral along which the dam moves.
21. A self-propelled frame having a dam thereon and concavo-convex guides on said frame so arranged that their convex faces may contact with the sides of a lateral, said guides being at the extreme forward end of the frame.
